UNITED STATES PATENT OFFICE

FRIEDRICH MERK, OF FRANKFORT-ON-THE-MAIN, GERMANY

SELECTOR FOR AUTOMATIC TELEPHONE EXCHANGES

Application filed March 4, 1929, Serial No. 344,105, and in Germany March 5, 1928.

This invention relates to selectors for automatic telephone exchanges and relates more particularly to the so-called panel selectors or selectors with a flat bank multiple field.

- 5 It is usual to compose the flat bank multiple of such selectors from separate bank strips and to secure it to frameworks composed of sectional iron which rest on the floor of the telephone exchange and are secured thereto. 10 This known arrangement has caused many defects and it is the purpose of the invention to provide an improvement in this known arrangement.

According to the present invention, the flat bank multiple, composed of separate bank strips, is not applied directly to the framework—which in addition to the selectors also supports other apparatus, particularly relay sets and the like—but to a separate independent frame on which are mounted only the flat bank multiple and the movable parts of the actual selector, which frame is provided with securing means for its attachment to the framework. This separate frame therefore carries the bank strips forming the flat bank multiple and the setting members or slides of the selectors which are movable over the flat bank multiple.

The invention makes it possible, in selectors 30 of this type (bar selectors or panel selectors) to conveniently obtain in an efficient manner the accurate mounting of the parts relatively to one another, which is usually only obtained with difficulty, and to prevent any inaccuracies and variations in the supporting points from having a deleterious action on the selectors.

A further object of the invention is to provide against any possible bending of the bank strips by employing supporting members which support and secure the separate bank strips not only at their ends, but also at a number of points intermediate their ends.

The invention is illustrated diagrammatically in the accompanying drawings, wherein:

Figure 1 is an elevation of a separate supporting frame arranged according to the invention with five bank strips, on the front of which are formed six contact fields; attention 50 being drawn to the fact that the rear side has

a substantially similar appearance and is provided in a similar manner with contact fields.

Figure 2 is a partial elevation of a corner of the frame on enlarged scale.

Figure 3 is a cross section of the frame, 55 also on enlarged scale and taken on the line 3—3 of Figure 2.

Figure 4 shows an elevation of one side of a somewhat modified construction of frame according to the invention.

Figure 5 is a corresponding partial plan; and

Figure 6 shows the frame of this invention mounted on a supporting structure constructed substantially in the usual manner.

The parallel bar-like parts 1, 2, 3 and the side parts 4, 5 arranged at right angles thereto, and connected together by any suitable means such as screws, rivets or the like form the separate frame constituting the main feature of my invention.

In the drawings, the connection is shown by way of example as being effected by means of screw bolts, and gusset plates 6, 7 are provided for the purpose of stiffening the frame. 75 Beyond the side portions 4, 5 project the ends of the strip 1 and the gusset plates 6, 7 and these parts are provided with holes 30 and 31 in order to secure the frame as a whole in the manner shown in Figure 6 to a supporting 80 structure 19 formed in the usual manner of two iron bars, the securing being effected by means of screw bolts 32 which are fitted through the holes 30, 31 and holes provided adjacent thereto in the supporting structure 85 19. The securing and arrangement is such that the parts 1, 2 and 3 when mounting the frame on the structure are horizontal.

The space between the two horizontal bars 1, 2 is filled with a plurality of superposed 90 bank strips 8, there being five of the same shown in this instance. These five bank strips form the bank multiple and each separate strip is made in a manner well known to every expert in this art, by layers of sheet metal 95 strips having projections and insulating strips, this arrangement not requiring further description. The projecting ends of the sheet metal strips form contact blades 33 at the front and rear of the framework as is in-

dicated diagrammatically in Figure 2. In each selector contact field, these blades form three vertical rows (see Figure 2) and in each bank strip 8 there are located at each 5 contact field, as can also be seen from Figure 2, ten superposed separate contacts in each row.

It is assumed that the width of the bank contact strips 8 is selected of such a size that 10 there are formed horizontally side by side in each bank strip 8, six fields each of three $\times$ ten contacts 33, and it is further assumed that between the bars 1 and 2 five such bank strips 8 are arranged one above the other.

15 The outer ends 9 of the strips 8 are provided on both sides in the manner indicated more clearly at the left of Figure 2, with soldering eyes 34. Figure 2 shows that the number of soldering eyes 34 in each end piece 20 9 is only half the number of contacts 33 in one partial field in order to permit a more convenient connection of the conductor wires (not shown), while it will be clear to an 25 expert in the art that on each side of the field 9, one-half of the connecting conductors is soldered on.

The bank strips 8 are secured by means of transverse bars 10 fastened at the front and rear of the multiple to the frame parts 1 30 and 2. Between the transverse bars 10 on the front and rear of the multiple, U-shaped cover bars 12 (Figure 3) are secured by headed screws 11, these bars forming cover bars 35 for the bank strips 8. The vertical spacing between the separate bank strips is regulated by the spacing between the holes in the bars 10 through which the screws 11 are drawn into the cover bars 12. It will be understood that the holes may be provided very 40 easily in accurately determined invariable intervals to obtain an invariable spacing of the bank strips 8 over the entire multiple field.

45 The strips 8 are secured to the cover bars 12 by any suitable known means, for example by lower bars 35 and by screws 36 which are drawn in from the top (see Fig. 3).

As the bars 10 produce an extremely rigid 50 connection of the upper and middle horizontal frame members 1 and 2, the upper portions of the vertical frame members 4 and 5, in so far as they are located between the bars 1 and 2, may be omitted. These parts are indicated in the drawings by the references 55 17 and 18.

By removal of the bars 10 on one side of the multiple, for example on the side of Figure 1 exposed to view, and release of the 60 screws 11, each separate strip 8 can be removed and replaced.

In the form of construction according to Figures 1 and 3, a guide bar 13 is secured over each strip 10 at a predetermined distance therefrom, the securing being effected by means of terminal bolts 40 and spacers

39. To the lower horizontal member of the frame are secured the driving mechanisms 15 for the bar insulators co-operating with the flat bank. These may be constructed in any usual manner and require no further description. They are adapted to move a selector slide 14 of the bar selector, which is movable and co-operates with the contacts 33, up and down.

These bars 13 serve to guide projecting 75 parts 37 of the selector slides 14 and to support at their lower end 38, the upper end of the driving work part 15, as shown in Figure 1, while between these parts any suitable connecting means such as screws, rivets or 80 the like, may be provided. The ends 38 may also engage with pockets of the driving mechanisms 15 or vice versa the driving mechanism may engage with pockets at the ends 38.

85 Figures 4 and 5 show a construction of a flat bank multiple according to the invention in which the number of connecting bars 10 may be reduced. While in the construction according to Figures 1 to 3 the selector slides 90 14 surround the edges of the bars 13 by projections 37, lateral bars 13' are provided on the selector slides in this modified form of construction which engage with corresponding slots 37' of transverse members 16, (see 95 Figure 5) which for example are secured on the cover bars 12 of the bank strip.

In the manner shown in Figure 6, relay sets 20 and 21 can be provided above and below the frames 1 to 3 for the bar selectors 100 on the structure 19, as indicated diagrammatically in the drawings, the relay sets 20 representing for example subscribers' relays which are secured in a readily detachable manner in vertical rows, and the relay sets 105 21 illustrating the relays necessary for the operation of the selectors.

Instead of securing the frame bars 1 to 5 as above described by means of four screw bolts 32, the securing thereof may be effected 110 in other ways, as for example by passing only the two screw bolts 32 through the holes 30 and corresponding holes in the structure 19 so that the entire selector arrangement will be suspended in the structure only at two points.

115 I claim:—

1. In an automatic telephone exchange having bar selectors including movable setting slides and flat bank multiple fields, a 120 rectangular frame comprising a plurality of horizontal and vertical frame members, bank strips forming the flat bank multiple, means for securing the bank strips in parallel arrangement between two of the said horizontal members of the frame, means on the said rectangular frame for holding the horizontal and vertical members rigid in relation to one another, and means for securing the 125 said frame to a selector structure.

2. In an automatic telephone exchange having bar selectors including movable setting slides and flat bank multiple fields, a rectangular frame comprising a plurality of horizontal and vertical frame members, bank strips forming the flat bank multiple, means for securing the bank strips in parallel arrangement between two of the said horizontal members of the frame, means on the said rectangular frame stiffening the horizontal and vertical members relatively to one another, guide-members supported by said stiffening means, and means at the upper end of the said frame for connecting it to a selector structure.
3. In an automatic telephone exchange having bar selectors including movable setting slides and flat bank multiple fields, a rectangular frame comprising a plurality of horizontal and vertical frame members secured together, a plurality of bank strips forming the flat bank multiple, a plurality of vertical transverse members connecting two of the said horizontal members of the frame and arranged at regular intervals apart, means securing horizontal bars to said transverse members, means securing each of the bank strips to one of the said horizontal bars, guide members in combination with said bank strips for guiding a setting slide in a vertical direction, means on said frame for stiffening the horizontal and vertical members relatively to one another, and means for securing the said frame to a selector structure.
4. In an automatic telephone exchange, flat bank multiple fields comprising a plurality of parallel horizontal rectangular bank strips with projecting insulated contacts, parallel bars, applied at the upper side and at the underside of each of the said bank strips, means for drawing together and clamping said bank strips between each two of the said bars, a plurality of vertical bars arranged at uniform intervals on opposite sides of the flat bank multiple, means for securing the upper of said horizontal bars to said vertical bars, two horizontal supporting members, means for connecting said vertical bars to said horizontal supporting members to form a rigid structure, and means for connecting the whole rigid structure to a selector structure.
5. In an automatic telephone exchange having bar selectors, including movable setting slides, driving means for said slides, a base plate for the driving means, and flat bank multiple fields; a rectangular frame comprising a plurality of horizontal and vertical frame members, bank strips forming the flat bank multiple, means for securing the bank strips in parallel arrangement between two of said horizontal frame members, means for securing said base plate for the driving means to a third horizontal frame member,
- means on said rectangular frame for stiffening its horizontal and vertical members relatively to one another, and means for securing the frame to a selector structure.
6. In an automatic telephone exchange having bar selectors, including movable setting slides, flat bank multiple fields and driving members for moving the setting slides over the flat bank fields; a rectangular frame comprising a plurality of horizontal and vertical frame members, a plurality of separate bank strips forming said flat bank multiple, a plurality of multiple transverse members connecting two of said horizontal frame members together and arranged at uniform intervals apart, means securing horizontal parallel bars to these transverse members, means securing one of said bank strips to each of said horizontal bars, a third horizontal member on said frame, means securing the driving members of the selectors to said third horizontal member, members on the second horizontal frame member for supporting the other end of said driving members, guide members in combination with the bank strips for guiding the selector slide in a vertical direction, and means for securing said frame to a selector structure.
7. In an automatic telephone exchange, flat bank multiple fields comprising a plurality of horizontal rectangular bank strips with projecting insulated contacts, parallel horizontal bars, arranged at the upper and lower sides of each of the bank strips, means for drawing together and clamping said bank strips between each two of said bars, a plurality of vertical bars arranged at uniform intervals on both sides of the flat bank multiple, means for securing the upper of the horizontal bars to said vertical bars, two horizontal supporting members, means for connecting the vertical bars to said supporting members so as to form a rigid structure, a third horizontal supporting member, means for connecting said rigid structure to said third supporting member, and means for connecting the rigid structure to a selector structure.
8. In an automatic telephone exchange with bar selectors, including movable setting slides, flat bank multiple fields and driving members for moving the setting slides over the flat bank fields; a plurality of horizontal rectangular bank strips with projecting insulated contacts, parallel bars, at the upper and lower sides of each of the said bank strips, means for drawing together and clamping the bank strips between each two of said bars, a plurality of vertical bars arranged at uniform intervals on opposite sides of the flat bank multiple, means securing the upper of said horizontal bars to said vertical bars, means for guiding the setting slides on the vertical bars, means connecting said vertical bars to the supporting members to form a rigid structure, a third horizontal sup-

porting member, means for connecting said rigid structure to said third supporting member, means for securing the driving members of the selectors to said third horizontal supporting member, sustaining members on the vertical bars for supporting the other end of said driving members, and means for connecting the rigid structure to a selector structure.

19 In testimony whereof I affix my signature.
FRIEDRICH MERK.
